DISPLAY PACKAGE FOR TOOTHBRUSH OR SIMILAR ARTICLE

Achim Peter Schultheiss, Iowa City, Iowa, assignor to Chemway Corporation, Wayne, N.J., a corporation of Delaware

Filed Sept. 16, 1963, Ser. No. 76,600

Term of patent 14 years

(Cl. D58—2)

FIG. 1

FIGURE 1 is a side elevational view of a display package for toothbrush or similar article showing my new design;

The rear of the display package is substantially plain.
I claim:

The ornamental design for a display package for toothbrush or similar article, as shown and described.
